UNITED STATES PATENT OFFICE.

HINSDALE SMITH, OF SPRINGFIELD, MASSACHUSETTS.

EXPLOSIVE-ENGINE.

SPECIFICATION forming part of Letters Patent No. 624,555, dated May 9, 1899.

Application filed October 4, 1897. Serial No. 653,933. (No model.)

To all whom it may concern:

Be it known that I, HINSDALE SMITH, a citizen of the United States, and a resident of Springfield, in the county of Hampden and 5 State of Massachusetts, have invented certain new and useful Improvements in Gas-Engines, of which the following is a specification.

This invention relates to improvements in gasoline and analogous explosive engines, the 10 object being to provide means which form part of the engine whereby the exhaust or expulsion of the dead gas from the cylinder-chamber will be complete after every driving or working stroke of the piston.

15 Another object of the invention is to simplify the engine and to render it readily reversible at pleasure.

The invention consists in the engine constructed substantially as hereinafter described, and set forth in the claims.

Reference is to be had to the accompanying drawings, in which the present improvements are illustrated, and in which—

Figure 1 is a central longitudinal sectional view through the cylinder and piston and other parts of the engine in which the invention is comprised. Fig. 2 is a view of the piston or piston-rod, to be hereinafter referred to, as showing a modified construction thereof 25 for permitting a contraction and distention thereof in the operation of the engine. Fig. 3 is a side view of a detent device as seen at right angles to its position shown at Fig. 1. Fig. 4 is a view of a modification of said detent 30 device.

Similar characters of reference represent corresponding parts in all of the views.

In the drawings, A represents the engine-cylinder, which is understood as being suitably mounted and supported, B being the piston, and C is the crank-shaft, having the crank C², with which the piston is connected.

a indicates the ingress-passage for the introduction into the cylinder, behind the piston, of the vaporized gasoline or other explosive fluid used as the motor agent, the same being adapted to be injected past the valve b² by the comparatively light spring b³.

50 G represents the exhaust-passage, connected with the port or valve-seat c², at which the valve d is applied.

The stem d² of the valve d for closing the exhaust-port has connected therewith the return bent end of a rod g, which ranges alongside the cylinder, being suitably guided, and this carries a lug or abutment-piece h, preferably adjustable thereon as secured by the set-screw h², and this lug h projects inwardly across the path of the forward portion of the 60 piston, so that the piston will at the completion of its forward working or explosion stroke in forcing the lug h slightly rearwardly through the connections just described and shown cause the opening of the valve d.

65 It will be perceived on reference to the drawings that the piston-rod is formed in two sections B² B³, the one telescoping the other and maintained normally in their most distended relations by the spring m.

70 The piston-rod section B³, which is engaged with the crank or wrist pin C², is tubular, while the piston-rod section B² has a portion thereof fitting in the tubular section, its inner extremity being necked down, whereby 75 the shoulder k is produced. The spring m is seated in the tubular piston-rod section and has its opposite end resting against the shoulder k. The said section B³ has the opposite slots n n, in which the extremities of 80 the guiding-pin n², which is passed through a transverse opening therefor in the piston-rod section B², have a sliding guiding fit.

85 In this type of engine the piston B has its thrust or working stroke by reason of the exploded gas in the cylinder-chamber behind it, it working by momentum on the relatively intermediate reciprocations.

90 The spark for causing the explosion of the gas after the same has been introduced into the cylinder and been compressed by the piston and when the piston is at or near its rearward limit is produced at e by the forming of an electric circuit, which is adapted to be periodically closed with the exception of 95 the slightly-separated points at e, between which the current jumps at the proper time, making the spark, and while the spark-producing device embodies no novelty as to any broadly-considered aspect thereof it will be 100 pointed out to consist in the parts and connections, as follows: The stem e², having its inner end terminating near a part e³, which is substantially a part of the cylinder-case,

has connected therewith the wire e^4 , running to the contact e^5 , and the adjacent contact e^6 is by a wire e^7 connected to a contact or finger e^8 , supported on and insulated, as seen at 20, 5 from the engine-body or cylinder-case D. A battery is "connected in" in the ordinary way in one of the wires constituting the circuit, as aforesaid.

There is an arm e^{12} affixed upon and radi- 10 ally extended from the crank-shaft, the outer end portion thereof being by the insulation v cut out from electrical connection with the crank-shaft, the extremity of this arm e^{12} having in its revolution a wiping contact on and 15 disengagement from the paired adjacent contact pieces or fingers $e^5 e^6$. The said contact-fingers $e^5 e^6$ are mounted on a lever f , normally stationary, but adapted to have its position changed from a center of movement which is 20 coincident with the axis of the crank-shaft.

Supported on and movable in unison with the piston or what is in substance the same, the piston-rod section B^2 , is the forwardly and longitudinally extending spring contact 25 plate or finger e^9 , carrying at its end the incline 21, the position of which is adjacent a second inclined block 22, mounted on the side of the piston-rod section B^2 .

The contact fingers or plates $e^8 e^9$ are ar- 30 ranged angular, the one relatively to the other, as seen in the drawings.

The rod g , connected with the exhaust-valve d , has its end which is toward the crank-shaft provided with the enlargement p , the forward 35 end of which is conical and which is disposed when the valve is closed adjacent the out-turned ends 2 of the opposing spring-arms q , the intermediate portions of which arms are arranged convergent, the one relative to the 40 other, as seen in Fig. 3. When the valve is opened, the rod g has the enlargement p thereof borne upon with a yielding pressure by the reaction of the convergent arms q , so as to retain the valve in its open position and yet not 45 to obstruct its being closed when borne against by the piston, as hereinafter explained, with a positive and sufficiently forcible pressure to overcome the bind upon the said enlargement p by the spring-arms which serve as the de- 50 tent therefor. The said enlargement may, as shown in Fig. 3, consist of a cylindrical fixture on the rod g , having a conical forward end; but the precise construction of this detent is 55 regarded as unimportant, as there are devices acting in substantially the same manner which may be utilized for the same effect—such, for instance, as represented in the view of the modification in Fig. 4, in which the opposing arms q^2 , which are divergent, have their 60 extremities by the links p^3 pivotally connected to the adjacent end of the rod g in the manner of toggles, one pair of the members of which, as seen, are resilient and have reaction toward each other. As the rod is endwise moved to 65 the position indicated by the dotted line in Fig. 4 the spring-arms $q^2 q^2$ are spread wider apart or farther divergent up to the time the

pivots are brought in line; and then as the rod completes this endwise movement the spring-arms react and again resume their normal po- 70 sitions, so that in order for the rod to again resume its position (shown by the full lines) such forcible pressure must be exerted there-against as to again spread the spring-arms to permit the links of the toggle to assume their 75 reversed or original position.

Now assuming after a stroke on an explosion that the valve d has been opened by the abutment of the piston against the lug h on rod g , it remains open by reason of the detent de- 80 vice at o engaging the rod, and through it holding the valve d in its opened position. Now as the piston moves with its piston-rod distended under the reaction of the applied spring m toward the head of the cylinder, and finally 85 to abutment against the inner wall of the cylinder-head, it positively forces out substan- tially all the dead gas remaining after the ex- plosion, and at the very end of its rearward stroke in contacting against the valve d di- 90 rectly and bodily closes said valve, the spring m being more powerful than the detaining force of the device $p q$. As the piston next moves by the action of momentum of the en- gine forwardly the considerable suction there- 95 by created in the cylinder causes the open- ing of the valve b against its comparatively light spring, permitting the introduction into the cylinder behind the piston of the sufficient quantity of gas or vaporized hydrocarbon or 100 other fluid employed as the motor agent. The piston again rearwardly moving compresses the gas or explosive fluid, which is elastic and capable of being compressed to occupy but a fraction of its normal volume, and in the com- 105 pression the piston and its piston-rod section B^2 has a movement of contraction relative to the piston-rod section B^3 and the crank, the forward end of section B^2 bottoming against the closed or solid forward end of section B^3 , 110 so that the explosion which takes place at the completion of the compressing action reacts against the piston, which has a piston-rod now capable of no further contraction, but in its driving action to all intents and purposes the 115 same as a simple integrally-formed piston-rod connecting the piston and the crank.

The discharge or expulsion of practically all of the dead gas remaining in the cylinder-chamber directly after the explosion-stroke 120 and before the introduction of the supply of the gas or vapor for the next stroke is very important and advantageous in acquiring the full efficiency of the gas and in assuring the certainty of operation of the sparking devices. 125

It will be explained that by the provision of the normally open contact parts e^8 and e^9 notwithstanding the terminals e^5 and e^6 are joined at every rotation of the crank-shaft as the arm e^{12} comes around upon said terminals there will not be a closing of the circuit, for it is to be pointed out that the parts e^8 and e^9 are not joined at every forward stroke of the piston, but they are joined at or near the 130

end of every second or compression stroke, and this will be seen to be for the reason that in its forward stroke next after the explosion or working stroke the piston is at its maximum distance from the crank, the spring being then uncompressed, and the incline 21 of contact-plate e^9 will merely pass the inclined contact e^8 without touching it; but in its rearward gas-compressing movement the piston and 5 piston-rod section B^2 moving endwise relative to the piston-rod section B^3 assures the action of the one incline 21 against the other 22 and offsetting of the extremity of spring-plate e^9 , so that the path of this extremity as it moves 10 with the piston to the completion of said gas-compression action, just above referred to, is such that the said plates $e^8 e^9$ will contact at the proper time for the making of the spark, which is simultaneous with the instant that 15 20 the arm e^{12} is in wiping contact on the terminals $e^5 e^6$. It will be understood that by slightly swinging the lever f upwardly or downwardly the contacting arm e^{12} will have its wiping action on the contacts $e^5 e^6$ correspondingly 25 earlier or later in the revolution of said arm, and thus the instant of producing the spark may be determined to a nicety. It is also to be noted that the piston operates to open the exhaust-valve only at every other stroke— 30 viz., the explosion-stroke—as the forward end of the piston does not reach the abutment h except at the time it moves to its forward limit and when it is in its contracted relation to the crank under the pressure of the exploded gas.

I do not wish to have the invention considered as necessarily limited to employment in a gas-engine of a type comprising novel features as claimed by me of means by which 40 the explosion is necessarily accomplished by electrical spark-producing appliances, for while these devices are believed to embody specific features of novelty properly herein claimed other means for the ignition of a 45 known character may be employed, and, again, while the invention in part comprises the co-operative combination of the piston contractible relative to the crank-shaft, substantially as described, with the exhaust- 50 valve d and its adjunct devices shown the piston, having the capability of the contraction and distention relative to the crank-shaft for the principal object stated, may be employed in an engine of this general type 55 in which the exhaust-valve is independently operated and controlled.

I do not wish to limit myself to the constructions shown in Fig. 1, whereby the piston is capable of assuming the relations of 60 contraction and distention relative to the crank-shaft, for other constructions of parts differing in form and arrangement may be substituted to the same end, and in Fig. 2 the piston-rod is shown in two sections, the 65 one telescoping the other and the one operating against an air-cushion at x in the sub-

chamber y through the medium of a liquid, (indicated at z .)

I regard the piston and the piston-rod as a unit, the same having between the end face of 70 the piston which receives the explosive impact and the place of connection with the crank-shaft the capability of change in longitudinal dimensions, and while the location of the means for this purpose toward the crank- 75 shaft is the preferable one the head of the device—that is, the piston itself—might be made in two sections, the one cushioning on the other with good results; but as the head of the piston is subject to heat in the continued 80 operation of the engine the spring or other medium of yielding resistance would in time become disadvantageously affected thereby.

Having thus described my invention, what 85 I claim, and desire to secure by Letters Patent, is—

1. In a gas-engine of the character described, the combination with the cylinder having an exhaust-passage, leading therefrom, provided with a valve which opens inwardly to the cylinder, and provided with a valved gas-inlet passage, and the crank-shaft, of a piston comprising, between its rear end and its connection with the said shaft, members which are movable one relative to the other, and provided with a reacting interposed cushion, whereby as the piston moves rearwardly against gas which has been entered in the cylinder, the said piston members will assume contracted relations, but whereby as the piston moves rearwardly in the absence of gas in the cylinder, its members will have their normal, distended, relations, substantially as described, a device 90 connected with the exhaust-valve for opening it, and all so arranged that the piston at or about the forward limit of its working stroke operates said valve-opening device, the piston while in its distended relation on the rearward stroke, closing the valve. 95

2. In a gas-engine, the combination with the crank-shaft, the cylinder having the valve and the valve-operating rod provided with an abutment, of a piston comprising, between 100 its rear end and its connection with the said shaft, members which are movable one relative to the other, and provided with a reacting interposed cushion, whereby as the piston reciprocates alternately, during the presence 105 or absence of gas in the cylinder, said members will assume respectively contracted and distended relations, substantially as described, one of said movable piston members being adapted on its alternate forward strokes, 110 in its contracted relation, to operate against said abutment and open the valve.

3. In a gas-engine, the combination with the crank-shaft, the cylinder having an inwardly-opening valve and means for periodically 115 opening the valve whereby it occupies a position within the inner end wall of the cylinder. 120

der, of a piston comprising, between its rear end and its connection with the said shaft, members which are movable one relative to the other, and provided with a reacting interposed cushion, whereby as the piston reciprocates alternately during the presence or absence of gas in the cylinder, said members will assume respectively contracted and distended relations, substantially as described, one of said movable piston members being adapted on its alternate forward strokes, while in its distended relation, to operate directly against the valve, forcing it closed.

4. In a gas-engine, the combination with the crank-shaft, the cylinder having the valve and the valve-operating rod *g*, provided with an abutment *h*, of a piston comprising between its rear end and its connection with the said shaft, members which are movable one relative to the other, and provided with a reacting interposed cushion, whereby as the piston reciprocates alternately during the presence and absence of gas in the cylinder, said members will assume respectively contracted and distended relations, substantially as described, one of said movable members being adapted on its alternate forward stroke in its contracted relation to operate against said abutment and open the valve, and a detent device for engaging the valve-operating rod *g*, substantially as described.

5. In a gas-engine, the combination with the cylinder and crank-shaft, of the piston constructed to be contractible and distensible between its rear end and its connection with the crank-shaft and having the interposed reacting cushion, adjacent points *e*² *e*³ within the cylinder-chamber, electric conductors connecting said points comprising a source of electrical supply, and in connection with plates which are on said movable piston members and means for bringing said plates into contact at every working or explosion stroke, of the piston, substantially as and for the purpose set forth.

6. In a gas-engine, the combination with the crank-shaft, piston and cylinder, having the adjacent points *e*² *e*³, the two terminals *e*⁶ *e*⁷ and a support *f* mounted for an adjusted swinging movement from a point coincident with the axis of the crank-shaft on which said terminals are supported, the arm *e*¹² on the crank-shaft for uniting the said terminals at every rotation of the crank-shaft and electric conductors for providing connection between said terminals and said points *e*⁶ *e*⁷, one thereof having connected therein a battery, substantially as described.

7. In a gas-engine having the cylinder and contractible and distensible piston, substantially as described, the separated, but adjacent sparking-points *e*² *e*³ in the cylinder and

circuit-conductors therefor, having connected therein a battery, the one comprising as connected therein, the plate *e*⁸ insulated on the engine-case, the spring-plate *e*⁹ mounted on one of the movable piston members, a cam or incline 22 supported on the other movable piston member against which the plate *e*⁹ impinges as the piston members assume their contracted relation whereby a part of the said plate *e*⁹ is transversely moved so that its path as it moves bodily in unison with the piston, will insure this plate contacting against the plate *e*⁸, substantially as described and for the purpose set forth.

8. In a gas-engine, the combination with the crank-shaft, the cylinder having the valve and the valve-operating rod *g* provided with an abutment *h* and an enlargement *p*, of a piston comprising the two members and an interposed reacting cushion whereby said members are adapted to alternately assume the contracted and distended relations, substantially as described, one of said movable members being adapted, in the operation of the engine, on its alternate forward stroke, and in its contracted relation, to act against said abutment and open the valve, and the paired spring-arms *q* *q* having the outturned ends 90 between which said enlargement of the rod *g* may be forced, and thereby temporarily detained, substantially as described.

9. In a gas-engine, the combination with the crank-shaft, having thereon the arm 12, and the cylinder provided with the valved gas-ingress passage and a valved exhaust-passage and having the adjacent sparking-points *e*² *e*³, of the rod *g* connected with the exhaust-valve and having the abutment *h* and a detent device applied to operate on said rod, of the piston comprising the head and piston-rod member *B*², provided with the spring-plate *e*⁹, and the telescoping member *B*³ having the incline 22, and the interposed spring *i* between said piston-rod members, the movable support *f* having the two insulated terminals *e*⁶ *e*⁷ supported thereon, a wire running from one of said terminals to said sparking-point *e*², the plate *e*⁸ insulated on the engine-body, and a wire running from the other of said terminals, to said plate *e*⁸ and one of said wires having connected therein a battery, all substantially as described and for the purpose set forth.

In testimony that I claim the foregoing as my invention I have signed my name, in presence of two witnesses, this 1st day of October, 1897.

HINSDALE SMITH.
